ATTORNEY

UNITED STATES PATENT OFFICE

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK

CIRCUIT FOR X-RAY MULTIPLE-TUBE STANDS

Application filed December 8, 1927. Serial No. 238,512.

The present invention has to do with electrical circuits and relates particularly to a circuit adapted to be used in conjunction with the multiple X-ray tube stand or tube holder, for which application for patent has been made in the name of Julius B. Wantz and Julius J. Grobe, under date of December 3, 1926, Serial No. 152,847. This application is a continuation in part of the prior 10 application of Julius B. Wantz, serially numbered 169,734 entitled "Circuit for X-ray multiple tube stand" and filed February 21, 1927.

Radiography has made tremendous strides 15 within the last two or three years. The improvements in tube structure and tube performance have resulted in finer X-ray photographs than have ever heretofore been made, and the improvements in X-ray apparatus 20 have made it possible to obtain radiographs without guess-work.

Until relatively recently, however, photographs by X-light were made without any 25 certainty as to whether the part desired to be shown in the radiograph was actually being photographed.

With the combination of fluoroscopic screens with the various X-ray apparatus used for photography and when means for 30 quick change from fluoroscopy to radiography were installed, the ability of an operator to obtain a satisfactory radiograph was many times multiplied.

One of the principal obstacles which has 35 been met when combining fluoroscopic screens and radiographic outfits, however, has been that the two voltages required, the one for radiography and the other for fluoroscopy, are so entirely different that it is difficult with the ordinary commercial X-ray 40 apparatus to successfully obtain the benefit of a prior or previous fluoroscopic examination for disclosing the proper object position for a radiograph.

45 Almost invariably, when the ordinary type of X-ray apparatus is employed, the patient to be photographed will move during the period adjustments are being made to change the character of the voltage from that for fluoroscopy to that for radiography. This

unhappy condition was a factor in the invention of the multiple tube stand, and other apparatus, for the purpose of facilitating the rapid change of an X-ray apparatus from a setting for fluoroscopic work to a setting for 55 radiographic work, or vice versa.

In order to satisfactorily change from a fluoroscopic voltage to a radiographic voltage, it is necessary in the hot cathode type of tube to change the voltage impressed across 60 the electrodes within the tube and to anteriorly or concurrently modify the electromotive force impressed upon the filament forming a part of the cathode of a tube. This is true whether one tube or two or more tubes 65 are employed in a single apparatus.

Ordinarily, the high tension voltage impressed upon the electrodes of a tube is controlled by an auto transformer. The adjustments in respect to such auto transformer are 70 coarse, and may be somewhat quickly obtained by adjusting the control handle upon a conventional auto transformer, generally contained in a control stand.

But very accurate adjustment is necessary 75 with respect to the voltage impressed upon the filament of a tube.

An adjustment for the auto transformer for the current impressed across the electrodes may be disturbed frequently because 80 so readily reobtained. The adjustment for the filament, however, is difficult to obtain and once determined should seldom be varied. Further, an adjustment for fluoroscopic examinations or an adjustment for radiographic work once obtained for the filament 85 should be maintained, if possible, because difficult to obtain to an accurate degree and because of the time required to procure. Certainly, good practice and economy of time 90 forbids frequent broad changes of the adjustment required to heat a filament for a fluoroscopic current to an adjustment required in conjunction with the high voltage impressed upon the electrodes of a tube for radiographic work.

The reason for this is the sensitivity of the filament which is so great that a very delicate control member or filament current regulator is generally employed in well assembled 100

X-ray apparatus. A great number of turns of the contro handle of such a device is necessary in order to change it from the adjustment employed for radiography to that necessary for fluoroscopy, or vice versa.

5 The present invention concerns the circuit or circuits to the filament of a tube, and the objects of the invention are to provide a plurality of separably maintainable adjustments 10 for a filament so that in changing from fluoroscopy to radiography, rather than make a change in the adjustment of a single unit controlling the intensity of the electromotive force applied to the filament, an auxiliary 15 filament current transformer is brought into play and used in the second adjustments.

There are a number of ways which I have 20 conceived in which circuits may be arranged for the provision of a multiple adjustment 25 of filament current. The principle of the present invention is the provision of one control means and transformer for the filament having in combination therewith a second (or third, etc.) control means and transformer 30 whereby a current of different intensity from that impressed upon the filament through the first control means and transformer may be impressed upon such filament and controlled by such second (or third, etc.) control means 35 and transformer.

It is quite manifest that a circuit may be arranged with two step-down transformers. It is equally manifest that two filament current control means may be employed with said 45 transformers and obtain the same result as when a single control means is used in conjunction with two transformers.

There is submitted with his application a 50 single sheet of drawing schematically illustrating a circuit suitable for obtaining the objects herein described.

In such drawing, a tube stand is disclosed in plan view. Such stand includes a vertical column 10 upon which a tube holder is disposed. The tube holder 11 is counterbalanced by a weight (not shown) adapted to reciprocate within the column 10, the cable 12 to such counterweight and a pulley 13, over which it passes, being shown at the top 55 of the column 10.

The multiple tube holder 11 comprises a main carriage 14 swivelly disposed at 15 up on a member 16 movable vertically upon the column 10 and it has side arms 17 terminating in a tie-rod 18. The side arms 17 provide tracks for a tube supporting board 19 upon which two (or more) tubes 20 are mounted, said board being supplied with 60 roller bearings 21 at its opposite sides. The tube board 19, therefore, is adapted to be moved intermediate the main carriage 14 and tie-rod 18 along the side arms 17.

The switch S disclosed in the drawing is 65 adapted to be actuated by the movements of the tube board 19, so that when one of the

tubes 20 thereon is in operable position, the switch S is in one extreme position, but when the other tube 20 is in operable position, the switch S is oppositely disposed.

At the right hand side of the drawing, one 70 of the high tension conduits 22 is shown, and as will be hereinafter pointed out, the other high tension conduit may be also employed as a filament current conduit. The other high tension line 22^a is connected to the cathode 75 and one side of the secondary circuit of the filament may be employed for such purpose.

Wherever, hereinbefore or hereinafter "heated cathode" tube or "hot cathode" X-ray tube, or a similar expression is employed, an X-ray tube having an electrode adapted to be electrically energized for the purpose of controlling the passage of high tension intermediate the two main electrodes of a tube is intended. Such an electrode is sometimes referred to herein as an electron emitting electrode.

80 Shields 23 are adapted to be used about the tubes 20 as is now common in the art, such shields being opaque to X-ray light 85 and having the general contour of the tube 20 about which they are disposed except for the window to allow the passage of X-ray light.

Reference should be had to the first application referred to above for an illustration 90 of a multiple tube holder in a table and in a stereoscope device. Such devices have a rotating or sliding tube holder in which the invention may be utilized as well as in the tube stand here illustrated.

Generally, from a single source of current, there is adapted to be delivered at a terminal or terminals adjacent to a sliding or movable tube rack for a plurality of tubes (two as here shown), electromotive force of different magnitudes. The invention may readily be adapted to meet the requirements of other X-ray apparatus, as is apparent. The electromotive forces so delivered is for controlling the X-ray radiation.

100 In the multiple tube holders here disclosed and as shown in said prior application, the X-ray tubes are adapted to be moved into position for use one at a time and shifted as necessity requires.

Suitable contacts are generally provided in association with the sliding or rotatable tube carrier as the case may be so that each tube, as it moves into position, automatically establishes electrical connection with the circuit to the filament of the X-ray tube in operable position. The circuit here described may be substituted for the filament circuit set out in the prior application referred to.

110 Means are provided by a multiple position switch, or in some other manner, whereby, as an incident to the movement of one tube, or of the tube rack or holder, here a sliding movement, the circuit to the filament terminal is broken and the circuit is reestab-

lished at the time a second tube (or the same tube again) is moved into position in the stand for use.

The conduits from the alternating current source are indicated 1 and 2. Line 1 runs directly to the regulating members R^1 and R^2 . A separate conduit runs from each of said regulating members R^1 and R^2 to opposite sides of switch S. Line 2 runs to the center of the multiple position switch marked S.

Included in circuit with each of the current control members R^1 and R^2 is a filament current transformer, T^1 and T^2 , transformer 15 T^1 being regulated by member R^1 , and transformer T^2 being controlled by member R^2 . The secondary of each of the said filament current transformers T^1 and T^2 is directly connected to the contacts on the movable tube 20 holder as each tube is brought into a proper position for use.

By the use of the switch S which is adapted to be automatically actuated as an incident to the movement of the multiple tube holder, 25 contacts are made and broken in the proper order to provide suitable filament current for the tube or tubes attached to the multiple holder and about to have high tension impressed thereon.

30 In one position of the multiple tube holder, current force passes through the filament control means R^1 and transformer T^1 while in another position current passes through the filament control member R^2 and transformer 35 T^2 . These two circuits are of different character whereby a different potential is delivered through the contacts upon the stand engaging the contacts upon the movable tube holder.

40 Ordinarily one of the two circuits is adjusted for fluoroscopic work and the other for radiographic work. Of course, more than two tubes and two adjustments may be provided.

45 The high potential conduits, 22 and 22^a, the latter to the cathode of the tube 20, are adapted to be connected to the electrodes of the tubes upon the tube carrier one at a time by the contacts shown. The latter conduit is 50 closed as an incident to actuation of switch S. Buttons 25 at the end of the anode of the X-ray tubes 20 are adapted to come in contact with the spring actuated button 24 forming the terminal of the high tension current conduit 22 shown at the right of the figure in the drawing.

Movement of the tube carrier 19, therefore, 55 brings into play, first, the proper filament current and adjustment for the impression of the proper high potential by another switch means, and, secondly, adaptability to receive high tension electromotive force.

Instead of the movement of the multiple tube holder directly actuating the filament 60 current switch, or the filament current con-

trol or regulatory member, the movement thereof may provide a safety device, permitting of the establishment of certain predetermined contacts, the actual contacting being accomplished manually or by means other than the movement of the multiple tube holder 19.

When the invention is used in connection with a stereoscopic shift, the contacts in the switch S as well as the plunger contacts and both high tension and filament current are likewise adapted to be shifted with the stereoscopic shift.

I claim:

A holder for a plurality of X-ray tubes 80 shiftable to bring such tubes into operable position one at a time, in combination with means for impressing an electromotive force of a selected magnitude upon the electron emitting electrode of each of said X-ray 85 tubes employed, and comprising a plurality of circuits each including a transformer and a regulatory member, and a switch member actuated by movement of said holder to select the circuit to the electron emitting electrode 90 of each separate tube.
